UNITED STATES PATENT OFFICE.

MICHEL REY, OF PARIS, FRANCE, ASSIGNOR OF ONE-HALF TO JOSEPH DE WYCKOFF,
OF WESTMINSTER, ENGLAND.

WINDOW-SASH.

1,173,863.

Specification of Letters Patent. Patented Feb. 29, 1916.

Application filed September 27, 1913. Serial No. 792,234.

To all whom it may concern:

Be it known that I, MICHEL REY, a citizen of the French Republic, residing at 52 Rue de Passy, Paris, in the Republic of France, 5 have invented certain new and useful Improvements Relating to Window-Sashes, Particularly for Railway-Carriages and other Vehicles, of which the following is a specification.

10 This invention relates to window sashes particularly for railway carriages and other vehicles.

The window sashes of vehicles are usually so arranged as to open under the influence of 15 gravity and to remain closed by resting upon a ledge in the frame or door in which they slide, intermediate positions being maintained by means of a strap or the like which is attached at one end to the base of the 20 window sash and engages at different points in its length with a knob or button on the frame or door. Such window sashes, when in their raised or partly raised position, are liable to shake so much, during the travel of 25 the vehicle, as to produce an objectionable rattling noise or even cause fracture of the glass; moreover when released for lowering purposes they fall abruptly unless checked, and are therefore liable to cause the glass to 30 be broken; also, if by careless handling a traveler raises the window sash to its full height too suddenly, the shock may cause the glass to crack.

The means for clamping the window sash 35 when adjusted to any desired height are preferably of the kind consisting of members adapted to move in planes perpendicular to the face of the window sash, these members being pivoted at one end in the 40 known manner but rocked about their pivots by two bars transversely movable inwardly and outwardly across the frame or door near the bottom of the window opening. The rocking movement of the members, due to 45 their coöperation with the transversely movable bars, is preferably brought about by a special formation of the outer or engaging ends of these bars, the latter being for this purpose bent or otherwise formed with a 50 cam-like surface for engagement with the unpivoted ends of the members. The unpivoted ends of the said members, which may be in the form of rods, are preferably forked to accommodate the outer ends of the

transversely movable bars. The inward and 55 outward movements of the transverse bars may be effected by a handle on a spindle carrying a disk provided with pins for co-operation with the inner ends of the bars as hereinafter explained.

In order that the invention may be clearly understood, and readily carried into effect, the same will now be described more fully with reference to the accompanying drawings, in which:—

Figure 1 is an elevation, Fig. 2 a vertical section on the line 2—2 of Fig. 1, and Fig. 3 a horizontal section on the line 3—3 of Fig. 1, showing a railway carriage door in which one embodiment of the improved window 70 sash is incorporated. In Fig. 2 the center cross rail of the door is shown removed a short distance from the remainder of the door, for the sake of clearness of illustration. Figs. 4 and 5 illustrate apart from the 75 window sash and on an enlarged scale the system of pulleys, the spring, and the stranded wire used in the window shown in Fig. 1, for keeping it normally closed. Fig. 6 is a sectional plan of the clamping means and 80 operating handle drawn to a larger scale, and Figs. 7 and 8 are two elevations, illustrating the means for rocking the clamping rods by means of which the window sash is retained at any desired height in its frame. 85 Fig. 9 is a plan of the handle and coöperating parts for actuating the reciprocating bars shown in Figs. 6 to 8.

A is the lower part or panel of the door, B B are the vertical members or posts forming part of the window frame, and C is the cross piece or head. The lower part A of the door is made hollow as usual, to accommodate the window sash when lowered, and the posts B B are grooved or rabbeted to 90 allow the window sash to slide therein. In the construction illustrated, the window sash consists of a sheet of plate glass D furnished with a button D' for manipulating it, and with protective metal strips D² D² 100 on its vertical edges. At the rear of each of the vertical grooves in the posts B B is situated a metal casing E (Figs. 4 and 5) which contains a coil spring E' and two pulleys E² E², and is surmounted by two 105 pulleys E³ E⁴ as shown clearly in Figs. 4 and 5. The pulleys E², E² are mounted in a small frame E⁵ which is capable of slid-

ing vertically in the casing E and is normally thrust to the foot of the same by the spring E'.

One end of a stranded wire F, which is passed around the four pulleys E², E², E³ and E⁴, is secured to the casing E, at a point just below the frame in which the pulleys E³, E⁴ are mounted and the other end is secured to the window sash at a convenient point, for example by being bound around the pin D^x by which the metal strip D² is secured to the glass D. The strength of the spring E' is such that it normally keeps the window sash in its closed position. When therefore the window sash is released from its open or an only partly closed position, it automatically closes to its full extent; a pad of rubber or the like C' (Fig. 2) is placed in the groove of the cross piece or head C to prevent the glass from receiving a shock on arriving at its fully closed position. A pad C³ of rubber or the like at the bottom of the window opening serves to prevent rain from entering the interior of the panel A when the window is closed. It will of course be understood that when the window sash is lowered, the two pulleys E², E² and their frame rise in the casing E and compress the spring E', the pulley system serving to enable a comparatively long path of travel of the window sash to be accompanied by a comparatively short path of travel of the lower pair of pulleys.

The means illustrated for clamping the window sash in position at any desired height comprise (at each side of the window opening) a vertical rod G which is pivoted at its upper end in the upper end of the rabbet of the window post B and in fact constitutes one of the side walls of the groove in which the window sash slides, as shown clearly in Figs. 2 and 3. Each rod is U-shaped in section and embraces a strip of rubber G' which projects beyond the longitudinal edges of the rod. The lower end of each rod is forked to transversely embrace the corresponding outer end of a bar H at the bottom of the window opening. Each bar H is slidably housed in the cross rail at the top of the panel A (Fig. 2) and is inclined at its outer end, as seen clearly in Fig. 6, so that when it is reciprocated it acts as a cam and causes the pivoted rod G to move about its pivot in a plane perpendicular to the face of the window sash. An outward movement of the bar H, as indicated by the arrow in Fig. 6, causes the lower end of the rod G to move in the direction of the arrow shown adjacent to it in this figure, and thereby causes the rubber strip G' (Fig. 3) to press against the metal strip on the edge of the glass thereby keeping the window sash in its adjusted position as shown clearly in

Fig. 3. When the bars H H are retracted, the rods G G rock about their pivots away from the metal strips of the window sash and the latter then automatically closes under the influence of the springs E'. 70

One convenient form of mechanism for reciprocating the bars H H is shown in Figs. 7, 8 and 9. The inner ends of the bars work in a box J and are specially shaped so that their slots H' and their cut-away portions H², H² coöperate with one another to form tracks in which two diametrically situated pins K^x, K^o work in such a manner that when the disk K, on which the pins K^x, K^o are formed, is oscillated, the bars H H are reciprocated. This action will be evident from inspection of Figs. 7 and 8 and it need merely be mentioned that the disposition of the parts in Fig. 8 as compared with the disposition in Fig. 7 is obtained by turning the disk K from its position shown in Fig. 7 through one hundred and eighty degrees in a clockwise direction. The disk K is mounted or formed on the inner end of a spindle K' the outer end of which is furnished with a handle K² as shown clearly in Fig. 9.

The action of the apparatus as a whole will be readily understood by the foregoing description, but it may be explained that if the window is closed and it is desired to open it, the operator grasps the button, D', and draws the window sash down to the desired position in opposition to the springs E' on each side of the window, and then turns the handle K² in the direction that causes the transverse bars H H to rock the rods G G toward the window sash, thereby causing the rubber strips G', G' to press upon the metal strips on the edges of the window sash and hold the latter in position. In order to close the window again it is merely necessary to turn back the handle K² to its former position.

What I claim as my invention and desire to secure by Letters Patent of the United States is:—

1. The combination with a normally spring-closed sliding window sash and sash frame, of vertical rods mounted to swing about horizontal pivots on the frame in a direction perpendicular to the face of the sash and thereby exert pressure upon the vertical edges thereof, transversely movable bars at the bottom of the window opening for effecting the swinging movement of the aforesaid rods, a handle, and means whereby manipulation of the handle effects reciprocation of the bars, both outward or both inward, depending upon the direction of manipulation of the handle. 115

2. The combination with a vertically movable window sash and a frame therefor, of spring-actuated members housed in the vertical members of the frame for exerting 130

upon the two sides of the sash a closing force sufficient to keep it normally closed, vertical rods pivoted at their upper ends to the vertical members of the window frame in positions such that they are capable of being rocked in planes perpendicular to the face of the sash and when rocked toward the latter exerting pressure upon the vertical edges thereof, pads carried by the rods to serve as longitudinal bearing surfaces, two transversely movable bars in approximate alinement with one another, the outer ends of the bars engaging with and shaped to have a cam-like effect upon the lower ends of the pivoted rods, a disk provided with pins coöoperating with the adjacent ends of the bars to effect reciprocation of the same when the disk is oscillated, a spindle to which the disk is fixed, and a handle for turning the spindle.

3. The combination with a sliding window sash and sash frame, of vertical rods mounted to swing about horizontal pivots on the frame in a direction perpendicular to the face of the sash and thereby exert pressure upon the vertical edges thereof, transversely movable bars at the bottom of the window opening for effecting the swinging movement of the aforesaid rods, a handle, and means whereby manipulation of the handle effects reciprocation of the bars, both outward or both inward, depending upon the direction of manipulation of the handle. 25

In testimony whereof I affix my signature in presence of two witnesses.

M. REY.
